UNITED STATES PATENT OFFICE.

STEPHEN F. F. KNEPLEY, OF WILLIAMSPORT, PENNSYLVANIA.

SILO.

1,208,332.

Specification of Letters Patent. Patented Dec. 12, 1916.

Application filed June 20, 1916. Serial No. 104,726.

To all whom it may concern:

Be it known that I, STEPHEN F. F. KNEPLEY, a citizen of the United States, residing at Williamsport, in the county of Lycoming 5 and State of Pennsylvania, have invented certain new and useful Improvements in Silos, of which the following is a specification.

This invention has reference to silos, and 10 its object is to provide a door lock construction of particularly efficient character and to provide a splice free from objections to splices as heretofore constructed.

In accordance with the present invention 15 there is provided a door frame with openings therein and in most part similar to door frames as used in silos and the doors themselves may be of usual construction except in certain details to be hereinafter described.

20 The door locks comprise levers carried by the doors on opposite sides thereof, each lever having a stem portion and an eye portion on opposite sides of its pivot point, the lever being pivotally carried by the door, 25 and, furthermore, the door carries a pivoted bail having parts traversing the eyes of the levers in such manner that when the bail is lifted the levers are moved to the unlocked position and when the bail is lowered they 30 are moved to the locked position, and the bails then serve as ladder rungs.

With respect to the splices, the meeting edges are beveled at different angles and are provided with an intermediate spline, the 35 arrangement being such that the splice is self-draining and at the same time when the parts are driven together the different angles on opposite sides of the spline prevent the commonly experienced difficulty of splitting.

40 The invention will be best understood from a consideration of the following detailed description, taken in connection with the accompanying drawings forming part of this specification, with the further understanding that while the drawings show a 45 practical form of the invention, the latter is not confined to any strict conformity with the showing of the drawings, but may be changed and modified so long as such 50 changes and modifications come within the scope of the appended claims.

In the drawings, Figure 1 is a face view of the door frame of the silo with two of the doors in place. Fig. 2 is a longitudinal 55 central vertical section of the showing of Fig. 1. Fig. 3 is a section on a larger scale

than Figs. 1 and 2, of a bevel lug and a portion of one of the locking levers. Fig. 4 is a perspective view of the locking lever as viewed from the face next to the door. Fig. 6C 5 is a section on the line 5—5 of Fig. 4 with a portion of the bail shown in dotted lines. Fig. 6 is a perspective view of one of the beveled lugs. Fig. 7 is an edge view of two meeting portions of sections of a stave showing the splice.

Referring to the drawings, there is shown a door frame consisting of stiles 1 and lintels 2 after the usual manner of constructing silo door frames, while back of the lintels 70 are battens 3. The form of door frame described provides a series of superposed openings 4 for access to the interior of the silo, and adapted to close these openings are doors 5 which may be constructed of cross 75 strips 6 and upright battens 7, with the latter so spaced as to enter the openings 4 in close relation to the inner edges of the stiles 1. It will be noted that the doors are constructed of any suitable material, whether 80 wood, metal, or fibrous or other composition, with the battens 7 when the door 5 is in place about flush with the plane of the front of the door frame. When the door is made of strips of wood or the like, the 85 battens 7 serve to hold these strips together, and stiffen the structure, and when the door is made of some suitable composition the battens serve as stiffening members and in either case they serve as supports for parts 90 to be described. Near the top and bottom of each door, the doors being upright in the installed position, there is provided a bail 95 8 having angle arms 9 at the ends in turn ending in angle extremities 10 lodged in the battens 7, so that the extremities 10 form pivotal supports with the axis extending transversely of the door and the extremities 10 entering the respective battens 7 at the 100 facing edges of the battens.

Pivoted to each batten 7 near the upper and lower ends thereof is a lever 11 shown separately in Fig. 4, each lever 11 being secured to a respective batten by a pivot pin or bolt 12 traversing a suitable hole 13 105 through the lever. One arm of the lever is in the form of a stem 14 having one face 15 beveled, such face being the face toward the door on which the lever is secured. The end of the lever remote from the arm 14 is in the form of a loop 16 having an elongated eye 17 of sufficient width to permit a re-

spective arm 9 of a corresponding bail 8 to pass loosely therethrough. The long sides of the loop 16 about the eye 17 on the face of the loop 16 toward the door are beveled as shown at 18, so that the bail arm 9 may extend through the loop 16 at a considerable angle to a line perpendicular to the plane of the loop.

The stem 14 is of sufficient length to over-
10 ride a respective stile 1 when the lever 11 is about horizontal, and then the bevel face 15 is presented toward the stile 1. To prevent wear of the stile, which is usually of wood, a metal lug 19 is made fast to the stile
15 where it would otherwise be engaged by the stem 14, and this lug is beveled in conformity with the bevel face 15, so that when the lever 11 is about horizontal the beveled face 15 engages the bevel face of the lug 19, thus clamping or cramping the parts together and serving as a wedge connection to draw the door 5 into tight engagement with the inner faces of the stiles 1 and lintels 2, the beveled lug 19 being in effect a wedge.

25 When the doors are locked in position, the levers 11 are about horizontal and project oppositely one from the other, being made in rights and lefts, and the arms 9 of the bails 8 extend through the eyes 17 at an angle to both the horizontal and vertical, or, in other words, in a slanting position. This not only holds the levers in the locked position by the weight of the bail, but also holds the bail in outstanding relation to the door
30 35 with the yoke of the bail sufficiently below and far enough from the levers 11 and the outer face of the door to leave ample foot room, so that the yokes of the bails may be utilized as ladder rungs, these rungs being 40 so arranged as to occupy positions similar to the rungs of the ladder.

When it is desired to release a door, the bails are lifted, turning about the axes of the extensions 10 as pivots. The result is
45 that the arms 9 acting on the loops 16 tend to turn the levers on their pivots 12, the arms 9 moving lengthwise of the eyes 17 of the loops 16 until ultimately lodged in the ends of the loops remote from the stem 14.
50 This causes a rocking of the levers in a direction to move the stems 14 away from the wedge lugs 19 until the extremities of the stems 14 have approached sufficiently to clear the inner edges of the stiles 1, where-
55 upon the door may be readily moved in a direction toward the interior of the silo. Each arm 9 close to the extension 10 has a bend or shoulder 20 in which the end of the loop 16 remote from the stem 14 lodges
60 when the bail is lifted as far as permitted by the loop. This forms a temporary lock preventing the bail from falling of its own weight and requiring a force purposely applied to move it downwardly to again lock
65 the door. In the latter condition the bail

serves to hold the levers 11 against accidental movement to the unlocked position, because the arms 9 between the shoulders 20 and the yoke of the bail has a downward slant.

70 In silo construction the staves are sometimes spliced together by what is known as a self-draining splice. In Fig. 7 two sections 21, 22 of a stave are shown. The section 21 has on one side of the joining end a bevel 23 and on the other side a bevel 24, while the section 22 has matching bevels 25, 26, respectively. The section 22 carries a spline 27 and the section 21 is provided with a groove 28 to receive the spline 27. Ordinarily the bevels 23 and 24 and the matching bevels 25 and 26 have a relatively sharp angular slant about that of the matching bevels 24 and 26. The result is that when the two members of the usual splice are 85 driven tightly together the bevels in the member 22 act after the manner of a wedge and frequently split the corresponding end of the section 21. With the splice shown in Fig. 7 the bevels 23 and 25 are so obtuse as to 90 act similarly to shoulders without any tendency to split the parts, and also prevent any splitting action between the bevels 24 and 26. At the same time the bevels 23 and 25 have a downward slant in the installed 95 position of the parts which makes the splice self draining, but avoiding any tendency of splitting when the two members of the splice are driven firmly together.

100 The levers are pivoted close to the stiles with the bails engaging the levers at the ends remote from the stiles, wherefore the locking and clamping ends of the stems 14 of the levers engage the stiles close to the pivots and the doors may be tightly clamped 105 in place without undue stresses on the levers and without the necessity of guards or guides for the levers, so that the structure is to a corresponding extent simplified without sacrifice of strength.

110 What I claim is:—

1. In a silo, the combination with a door frame and a door having battens adjacent to the sides and located on the outer face of the door, of locking means for the door comprising a bail pivotally mounted at the ends in the battens and extending crosswise of the door with the bail movable about an axis crosswise of the door, and locking levers pivotally mounted on the battens and each having an elongated slot on the side of the pivot toward and traversed by the bail.

115 2. In a silo, the combination with a door frame and a door having battens adjacent to the sides and located on the outer face of the door, a bail having angle ends pivoted in the battens on an axis transverse of the door, and levers on opposite sides of the door pivotally mounted on the battens with each lever having the outer end movable into over-

riding relation to the corresponding side of the door frame, and the inner end on the side of the pivot remote from the door frame being provided with an eye elongated in 5 the direction of the length of the lever and traversed by a corresponding angle end portion of the bail.

3. In a silo, a door frame and a door having longitudinally arranged battens near 10 opposite sides of the door and spaced apart to set within a corresponding part of the door frame, a bail having angle ends entering the battens on an axis transverse of the door, and levers on the battens at opposite 15 sides of the door, each lever being a substantially straight structure pivoted intermediately to the batten with one end movable into overriding relation to the corresponding side of the door frame and the 20 other end formed with an elongated eye lengthwise of the lever and traversed by the corresponding angle end of the lever.

4. In a silo, a door frame and a door having longitudinally arranged battens near opposite sides of the door and spaced apart to 25 set within a corresponding part of the door frame, a bail having angle ends entering the battens on an axis transverse of the door, and levers on the battens at opposite 30 sides of the door, each lever being a sub-

stantially straight structure pivoted intermediately to the batten with one end movable into overriding relation to the corresponding side of the door frame and the other end formed with an elongated eye 35 lengthwise of the lever and traversed by the corresponding angle end of the lever, the eye in each lever being wider than the thickness of the bail and having the edges toward the door expanded or beveled to permit the 40 angle portions of the bail to slant outwardly and downwardly from the door when the levers are substantially horizontal.

5. In a silo, a door having levers near opposite edges of and spaced from the outer 45 face of the door and with their pivotal axes substantially perpendicular to the outer face of the door, each lever having the end on the side of the pivot toward the other lever provided with a substantially straight longitudinal slot, and a bail having angle ends 50 pivoted to the door and extending through the slots in the respective levers.

In testimony whereof I have affixed my signature in presence of two witnesses.
